APPARATUS FOR HANDLING ROLLS OF
FLEXIBLE SHEET MATERIAL

Arthur T. Lewis, Toronto, Ontario, Canada

Application February 13, 1945, Serial No. 577,686

17 Claims. (Cl. 242—66)

1

This invention relates to apparatus for handling paper rolls or rolls of other flexible sheet material in rewinding or slitting machines. Machines of this type are provided with two under drums spaced apart and rotatable in the same direction, and a spindle on which is wound the paper and which is placed in the valley between the drums. To get the spindle with its accumulated paper out of the machine and insert a fresh spindle is a time-consuming operation if done by hand. Sometimes the paper roll is large and difficult to move. Heretofore to facilitate removal of paper rolls resort has been had to expensive and complicated mechanism.

It is an object of the present invention to provide a simple, inexpensive mechanism of such form that it may be incorporated in new machines or added to old ones, and whereby the wound rolls of paper may be conveniently and rapidly ejected from the machine.

It is a further object of this invention to provide a roll ejecting mechanism in conjunction with mechanism for automatically returning a fresh spindle to winding position in the machine.

This invention will hereinafter be specifically described in combination with a paper rewinder and slitting machine with which it is particularly useful. However, it should be understood that the roll ejecting and spindle feeding mechanism is not limited to use with the particular machine disclosed herein.

Other and further objects of this invention will be apparent to those skilled in the art from the following detailed description and the annexed drawings which by way of preferred example illustrate one embodiment of the invention.

In the drawings like numerals of reference indicate corresponding parts in the different figures.

Figure 1 is a top plan view, partly broken away;

Figure 2 is a partial cross section showing the roll handling means in position ready to eject the full roll of paper;

Figure 3 is a cross section showing the roll handling means in position as the full roll is about to be ejected and the new spindle to be fed to the machine;

Figure 4 is a fragmentary horizontal section on the line 4—4 in Figure 2, on an enlarged scale; and

Figure 5 is a fragmentary rear section on the line 5—5 in Fig. 4.

The reference numeral 1 indicates the supporting frame of the machine; this part of the paper

winding apparatus or "rewinder," as it is commonly known, may be of any standard construction as it forms no part of the present invention.

As is usual in machines of this type the winding mechanism comprises a pair of rotatable under-drums 2 and 3 and a winding spindle 4 rotatably supported by said drums 2 and 3 and adapted to wind up the paper into a roll 5 on cores 16 by contact with said revolving under-drums 2 and 3. The under-drums 2 and 3 are suitably journaled in the frame 1 of the machine, and they are driven by any suitable means (not shown).

Resting on the paper roll 5 is a riding roller 6 which is rotatably mounted in a riding roller supporting frame 7. Said supporting frame comprises a cross member and end members on which are mounted shoes 9, 9. In a "Kidder" machine this riding roller is driven by means of suitable gears in synchronism with the bed rollers. Since this does not form a part of this invention, the driving means is not described or shown for the sake of clarity.

Each side of the frame 1 has vertically extending posts 11, 11, which are joined at their uppermost extremities by a transverse beam 13. The inner surfaces of these posts 11, are provided with guideways 11a, 11a extending along substantially the whole length of the posts. The outer surfaces of shoes 9, 9 of the riding roller supporting frame 7 are provided with grooves to travel along the guideways 11a. Thus, as the paper accumulates on the winding spindle and the diameter of the roll increases, the riding roller 6 in its supporting frame 7 will gradually travel upward. Also, when it is required to remove the full roll of paper from the machine the riding roller supporting frame may be lifted upwardly by means of the pulley system 16 in conjunction with cord 17.

The roller handling apparatus proper comprises a suspension member 20 which includes arms 21, 21 which are respectively hinged on the top of posts 11, 11 by hinges 12, 12. These two arms are joined by transverse bar 23. Pivotedly mounted to the lower part of the suspension member 20 is the lever member 24 which comprises hooking bars 25 and 26 having notches 25a and 26a and joined by transverse members 27. Pins 11 and 12 project outwardly from the sides of the hooking bars and provide pivots for the lever member 24 in the suspension arms 21. These pivot points are arranged substantially at the centre of gravity of the lever member 24, so that normally the lever member will be balanced

on its pivots. I find it desirable to provide longitudinal movement of the lever member along the suspension arm, and for this purpose I provide slots 73 in the suspension arm in which the pivot pins 71 and 72 may have longitudinal travel. Adjustable stops 80 and 81 limit the amount of possible longitudinal travel.

Extending from the shoes 9 of the riding roller supporting frame are cams 30. On each suspension arm 21 are cam followers 32 which are designed to co-act with the cams 30 in a manner which will be hereinafter described. The position of cam followers 3 on the suspension arms 21 can be altered by loosening screws 82, resetting the cam followers, and re-tightening the screws in holes 84.

While the machine is in operation and paper is being rolled on the spindle 4, the roller handling apparatus is placed in inoperative position by swinging the suspension member outwardly, that is in a sense away from the posts.

To remove a full roll of paper from the machine the suspension member 20 is swung inwardly and the hooking bars 25 of the lever member 24 engage the ends of the spindle 4, as shown in Fig. 2. Then the riding roller supporting frame 1 is lifted upwardly along the guideways 11a of posts 11 by pulling cord 17. As the riding roller supporting frame moves upwardly the cams 30 which form part of the shoes 9 come in contact with the cam followers 32 and thereby they gradually push the suspension member 20 outwardly. As the suspension member is swung outwardly the lever member 24 (which by means of its hooking bars 25 had previously engaged spindle 4 carrying the full roll of paper 5) will pull this roll back over the rear under-drum 3 and eject it on the receiving table 50. The notches in the hooking bars are so designed that once the paper roll is on the receiving table 50 it releases itself automatically from the said hooking bars and rolls down the receiving table by gravity.

The top surface of the hooking bars 25 is smooth and slopes downwardly at the hooked end, and upwardly extending flanges 51 are provided on each side thereof. Thus an empty spindle 53 having mounted thereon a plurality of cores 77 may be placed on it after the lever member 24 is adjusted to grasp the spindle 4. The ends of the spindle rest on the top surface of the hooking bars and longitudinal movement is prevented by the flanges 51. When the suspension member 20 is swung outwardly to eject the full roll 5 from the machine the lever member 24 will tilt slightly and the spindle will then roll downwardly and forwardly.

As the suspension member 20 is moved out the new spindle will roll down the hooking bars until its ends engage the riding roller frame 1. Extensions 7a at each end of the frame 1 extend downwardly over the ends of the filled spindle 4 and act as stops to hold the new spindle 53 on the hooking bars as their ends tilt downwards. When the extensions 7a release the spindle it rolls gently down the sloping ends of the hooking bars into position on the drums 2 and 3 ready for winding. The ends of the spindle will contact the rear side of the guideways 11a thus preventing the spindle from rolling over the front under-drum 2.

After the fresh spindle has been deposited on the under-drums the riding roller supporting frame is released, the roll handling apparatus being kept in the outwardly swung position, and

the machine is once again in operative position. A latch 52, which is better illustrated in Figure 1, secured to a suitable part of the frame may, if desired, be provided to hold the suspension member in outwardly swung inoperative position until it is desired to again position it.

To facilitate handling the suspension member 20 and lever member 24 I find it convenient to provide a suitable cord 55 attached to transverse bar 27 of the lever member and passing over beam 13 and extending downwardly within easy access to the operator. By pulling on this cord the operator can adjust the elevation and/or inclination of the lever member to the desired position to cause the hooking bars to engage the pins and retain same in horizontal position to support the new spindle. After the suspension arms have been swung outwardly to eject the paper roll 5, the cord 55 may be pulled to pivot the lever member causing the hooking bars to give the paper roll added impetus in its movement out of the valley between the under-drums and onto the receiving table.

Stop means may be attached to the cord to limit the extent to which the lever member may be pulled upwardly or dropped.

In rewinding operations it is necessary to spread some glue on the empty cores 77 in order to prevent the paper which is to be wound on it from slipping. In order to facilitate this operation I take advantage of the construction of the lever member to place in the space between the hooking bars 25 an open-topped container 60. Journalled in each end wall is a glue-spreading shaft 66 having on its surface enlarged parts 67. This container and shaft are so adjusted that the top of the enlarged parts 67 will touch the underneath surface of the cores 77 on the spindle 53 which is resting on the lever member and passes over said shaft 66. A glue compound is placed in the container to a level sufficient to wet the underneath portions of the enlarged parts 67 of the shaft 66. When a new spindle 53 is placed on the lever member it will pass over the container 60 and the enlarged parts 67 of the glue spreading shaft 66 will touch the cores 77 on the new spindle and apply glue to it. This feature saves the operator the trouble of manually applying glue to the spindle shaft. Pins 71 and 72 project outwardly from the sides of hooking bars 25, 26 and are longitudinally movable in slots 73 in suspension arms 21. Adjustable stops 80 and 81 limit the amount of movement. These pins 71, 72 provide pivots for lever member 24, all as previously described.

Slitting knives for cutting the paper into small rolls, which are used on the "Kidder" and other slitting machines, are omitted from the drawings since they do not form part of the invention and would obscure the disclosure of the invention.

It is thought that the construction and use of the invention will be apparent from the above description of the various parts and their purpose. It is to be understood that the form of my invention herewith shown and described, is to be taken as a preferred example of the same, and that various changes in the shape, size and arrangement of parts may be resorted to, without departing from the spirit of my invention.

It will be understood that it applies equally to the winding of sheets or webs of other flexible sheet material such as rubber, foil, textiles, or resinous films, such as cellulose acetate film, and it is to be distinctly understood that although the invention has been described in connection with

paper rolls for convenience, it is applicable likewise to the other materials mentioned above.

What I claim as my invention is:

1. Roll handling apparatus for flexible sheet material winding machines, comprising means for rotatably supporting a spindle; means for rotating the spindle to wind the sheet material therearound; means for feeding sheet material to the spindle; a suspension member; supporting means on which the suspension member is pivoted; a lever member pivotally mounted on the lower end of the suspension member and adapted to engage the spindle; and means for swinging the suspension member and lever member away from the spindle supporting means to eject the spindle from the spindle supporting means after the sheet material has been wound on the spindle.

2. Roll handling apparatus for flexible sheet material winding machines, comprising means for rotatably supporting a spindle; means for rotating the spindle to wind sheet material therearound; means for feeding sheet material to the spindle; a suspension member; supporting means on which the suspension member is pivoted; a lever member pivotally mounted on the lower end of the suspension member and adapted to engage the spindle; means for swinging the suspension member and lever member away from the spindle supporting means to eject the spindle supporting means after the sheet material has been wound on the spindle; and means for pivoting the lever member to adjust the angle thereof to the desired position for engagement with and ejection of the spindle.

3. Roll handling apparatus for flexible sheet material winding machines, comprising means for rotatably supporting a spindle; means for rotating the spindle to wind the sheet material therearound; means for feeding sheet material to the spindle; a suspension member; supporting means on which the suspension member is pivoted; a lever member pivotally mounted on the lower end of the suspension member adapted to engage the spindle and provided with a hook adapted to hook over a part of the spindle; and means for swinging the suspension member and lever member away from the spindle supporting means to eject the spindle from the spindle supporting means after the sheet material has been wound on the spindle.

4. Roll handling apparatus for flexible sheet material winding machines, comprising a spindle having cores mounted thereon; the ends of the spindle projecting beyond the ends of the cores; means for rotatably supporting the spindle; means for rotating the spindle to wind the sheet material therearound; means for feeding sheet material to the spindle; a suspension member; supporting means on which the suspension member is pivoted; a lever member pivotally mounted on the lower end of the suspension member adapted to engage the spindle and provided with hooks adapted to hook over the projecting ends of the spindle; and means for swinging the suspension member and lever member away from the spindle supporting means to eject the spindle from the spindle supporting means after the sheet material has been wound on the cores.

5. Roll handling apparatus for flexible sheet material winding machines, comprising means for rotatably supporting a spindle; means for rotating the spindle to wind sheet material therearound; means for feeding sheet material to the spindle; a suspension member having longitudinal slots at the lower portion thereof; supporting

means on which the suspension member is pivoted; a lever member pivotally and slidably mounted in the longitudinal slots of the suspension member and adapted to engage the spindle; means for swinging the suspension member and lever member away from the spindle supporting means to eject the spindle supporting means after the sheet material has been wound on the spindle; and means for pivoting the lever member to adjust the angle thereof to the desired position for engagement with and ejection of the spindle.

15 6. Roll handling apparatus for flexible sheet material winding machines, comprising means for rotatably supporting a spindle; means for rotating the spindle to wind sheet material therearound; means for feeding sheet material to the spindle; a suspension member having longitudinal slots at the lower portion thereof, said slots being provided with an adjustable upper and lower stop; supporting means on which the suspension member is pivoted; a lever member pivotally and slidably mounted between the adjustable stops in the longitudinal slots of the suspension member and adapted to engage the spindle; means for swinging the suspension member and lever member away from the spindle supporting means to eject the spindle supporting means after the sheet material has been wound on the spindle; and means for pivoting the lever member to adjust the angle thereof to the desired position for engagement with and ejection of the spindle.

20 7. Roll handling apparatus for flexible sheet material winding machines, comprising means for rotatably supporting a spindle; means for rotating the spindle to wind the sheet material therearound; means for feeding sheet material to the spindle; a suspension member; supporting means on which the suspension member is pivoted; spindle engaging means mounted on the lower end of the suspension member; a riding roller adapted to ride on the roll of sheet material as the spindle is being wound with sheet material; a frame in which the riding roller is rotatably mounted; means for lifting the riding roller frame 25 to raise the riding roller off the roll of sheet material when the spindle is wound; and means actuated by the lifting of the riding roller frame for swinging the suspension member and spindle engaging means away from the spindle supporting means to eject the spindle from the spindle supporting means after the sheet material has been wound on the spindle.

30 8. Roll handling apparatus for flexible sheet material winding machines, comprising means for rotatably supporting a spindle; means for rotating the spindle to wind the sheet material therearound; means for feeding sheet material to the spindle; a suspension member; supporting means on which the suspension member is pivoted; spindle engaging means mounted on the lower end of the suspension member; a riding roller adapted to ride on the roll of sheet material as the spindle is being wound with paper; a frame in which the riding roller is rotatably mounted; means for 35 lifting the riding roller frame to raise the riding roller off the roll of sheet material when the spindle is wound; a cam on the riding roller frame; a cam follower on the suspension member, said cam follower being adapted to be engaged by the cam 40 when the riding roller frame is lifted and to swing the suspension member and the spindle engaging means away from the spindle supporting means to eject the spindle from the spindle supporting means after the sheet material has been wound 45 on the spindle.

75

9. Roll handling apparatus for flexible sheet material winding machines, comprising means for rotatably supporting a spindle; means for rotating the spindle to wind the sheet material therearound; means for feeding sheet material on the spindle; a suspension member; supporting means on which the suspension member is pivoted; spindle engaging means mounted on the lower end of the suspension member; a riding roller adapted to ride on the roll of sheet material as the spindle is being wound with sheet material; a frame in which the riding roller is rotatably mounted; vertical guideways on which the riding roller frame slides; means for lifting the riding roller frame to raise the riding roller off the roll of sheet material when the spindle is wound; a cam on the riding roller frame; a cam follower on the suspension member, said cam follower being adapted to be engaged by the cam when the riding roller frame is lifted and to swing the suspension member and the spindle engaging means away from the spindle supporting means to eject the spindle from the spindle supporting means after the sheet material has been wound on the spindle.

10. Roll handling apparatus for flexible sheet material winding machines, comprising means for rotatably supporting a spindle; means for rotating the spindle to wind the sheet material therearound; means for feeding sheet material to the spindle; a suspension member; supporting means on which the suspension member is pivoted; spindle engaging means mounted on the lower end of the suspension member; a riding roller adapted to ride on the roll of sheet material as the spindle is being wound with sheet material; a frame in which the riding roller is rotatably mounted; means for lifting the riding roller frame to raise the riding roller off the roll of sheet material when the spindle is wound; a cam on the riding roller frame; a vertically adjustable cam follower on the suspension member, said cam follower being adapted to be engaged by the cam when the riding roller frame is lifted and to swing the suspension member and the spindle engaging means away from the spindle supporting means to eject the spindle from the spindle supporting means after the sheet material has been wound on the spindle.

11. Roll handling apparatus for flexible sheet material winding machines, comprising means for rotatably supporting a spindle; means for rotating the spindle to wind sheet material therearound; means for feeding sheet material to the spindle; a suspension member; supporting means on which the suspension member is pivoted; a lever member pivotally mounted in a vertical slot in the lower end of the suspension member and adapted to engage the spindle; means for swinging the suspension member and lever member away from the spindle supporting means to eject the spindle supporting means after the sheet material has been wound on the spindle; and means for pivoting the lever member to adjust the angle thereof to the desired position for engagement with and ejection of the spindle.

12. Roll handling apparatus for flexible sheet material winding machines, comprising a spindle having cores mounted thereon, the ends of the spindle projecting beyond the ends of the cores; means for rotatably supporting the spindle; means for rotating the spindle to wind sheet material therearound; means for feeding the sheet material to the spindle; a suspension member; supporting means on which the suspension mem-

ber is pivoted; vertical guideways along said supporting means; a riding roller; a riding roller supporting frame slidably mounted in said guideways; means for lifting said riding roller supporting frame; a lever member pivotally mounted on the lower end of the suspension member and provided with hooks adapted to hook over the projecting ends of the spindle; and means for swinging the suspension member and lever member away from the spindle supporting means and for pivoting the lever member to eject the spindle from the spindle supporting means after the sheet material has been wound on the spindle.

13. Roll handling apparatus for flexible sheet material winding machines, comprising means for rotatably supporting a spindle; means for rotating the spindle to wind sheet material therearound; means for feeding sheet material to the spindle; a suspension member; supporting means on which the suspension member is pivoted; hooking bars supported by the suspension member and adapted to engage the spindle and to also support a fresh spindle on the top surface thereof; and means for swinging the suspension member and hooking bars away from the spindle supporting means to eject the spindle supporting means after the sheet material has been wound on the spindle and deposit the fresh spindle on the means for rotatably supporting a spindle.

14. Roll handling apparatus for flexible sheet material winding machines, comprising a spindle; means for rotatably supporting the spindle; means for rotating the spindle to wind sheet material therearound; means for feeding the sheet material to the spindle; a suspension member; supporting means on which the suspension member is pivoted; vertical guideways along said supporting means; a riding roller; a riding roller supporting frame slidably mounted in said guideways; means for lifting said riding roller supporting frame; a lever member pivotally mounted on the lower end of the suspension member and provided with hooks adapted to hook over the ends of the spindle, said lever member being adapted to also support a fresh spindle on the top surface thereof; and means for swinging the suspension member and lever member away from the spindle supporting means and for pivoting the lever member to eject the spindle from the spindle supporting means after the sheet material has been wound on the spindle and to then deposit the fresh spindle on the means for rotatably supporting a spindle.

15. Roll handling apparatus for flexible sheet material winding machines, comprising a spindle; means for rotatably supporting the spindle; means for rotating the spindle to wind sheet material therearound; means for feeding the sheet material to the spindle; a suspension member having longitudinal slots at the lower portion thereof; supporting means on which the suspension member is pivoted; vertical guideways along said supporting means; a riding roller; a riding roller supporting frame slidably mounted in said guideways; means for lifting said riding roller supporting frame; a lever member pivotally and slidably mounted in the longitudinal slots of the suspension member and being provided with hooks adapted to hook over the ends of the spindle; and means for swinging the suspension member and lever member away from the spindle supporting means and for pivoting the lever member to eject the spindle from the spindle supporting means after the sheet material has been wound on the spindle.

16. Roll handling apparatus for flexible sheet material winding machines, comprising a spindle; means for rotatably supporting the spindle; means for rotating the spindle to wind sheet material therearound; means for feeding the sheet material to the spindle; a suspension member having longitudinal slots at the lower portion thereof and said slots being provided with adjustable stops; supporting means on which the suspension member is pivoted; vertical guideways along said supporting means; a riding roller; a riding roller supporting frame slidably mounted in said guideways; means for lifting said riding roller supporting frame; a lever member pivotally and slidably mounted between the adjustable stops in the longitudinal slots of the suspension member and being provided with hooks adapted to hook over the ends of the spindle; and means for swinging the suspension member and lever member away from the spindle supporting means and for pivoting the lever member to eject the spindle from the spindle supporting means after the sheet material has been wound on the spindle.

17. Roll handling apparatus for flexible sheet material winding machines, comprising means for rotatably supporting a spindle; means for rotating the spindle to wind sheet material therearound; means for feeding sheet material to the spindle; a suspension member; supporting means

on which the suspension member is pivoted; a lever member pivotally mounted on the lower end of the suspension member, said lever member comprising hooking bars adapted to engage the spindle and to also support a fresh spindle on the top surface thereof; gluing means extending between and below the hooking bars for contact with the surface of a core on the fresh spindle when the spindle is placed on the supporting bars; means for swinging the suspension member and lever member away from the spindle supporting means to eject the spindle supporting means after the sheet material has been wound on the spindle; and means for pivoting the lever member to adjust the angle thereof to the desired position for engagement with and ejection of the spindle and then to deposit the fresh spindle on the means for rotatably supporting a spindle.
